CLAIM

The ornamental design for a string light, as shown and described.

DESCRIPTION

FIG. 1 is a top, front perspective view of string light showing my new design, in a first configuration;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is an exploded top, front perspective view of the string light of FIG. 1 in a second configuration;

FIG. 9 is an exploded front view thereof;

FIG. 10 is an exploded rear view thereof;

FIG. 11 is a right side view thereof;

FIG. 12 is a left side view thereof;

FIG. 13 is an exploded top view thereof; and,

FIG. 14 is an exploded bottom view thereof.

The features shown in broken lines are portions of the string light forming no part of the claimed design. The line at the far right of the drawings terminating in the string light is a boundary line forming no part of the claimed invention.

1 Claim, 6 Drawing Sheets
